ELASTIC FLUID POWER PLANT

Filed May 3, 1932

Inventor:
Paul Dettenborn,
by *Charles V.ella*
His Attorney.

UNITED STATES PATENT OFFICE

PAUL DETTENBORN, OF BERLIN-STEGLITZ, GERMANY, ASSIGNOR TO GENERAL ELECTRIC COMPANY, A CORPORATION OF NEW YORK

ELASTIC FLUID POWER PLANT

Application filed May 3, 1932, Serial No. 608,907, and in Germany May 18, 1932.

The present invention relates to elastic fluid power plants, more particularly to the arrangement of reheaters or intermediate superheaters, or like apparatus for superheating or reheating elastic fluid.

It is known to use the fire gases of a boiler for superheating or reheating elastic fluid. In order to obtain the desired temperature of the superheated elastic fluid and to prevent burning of the conduits in the superheater, it is necessary to regulate the heat transferred to the reheater or superheater. Difficulties, however, may arise in case of fluctuating load conditions, particularly at 10 a sudden decrease in load where it is not possible to decrease the amount of heat transferred to the superheater or reheater fast enough to prevent damage of the heating apparatus by the fire gases.

One object of my invention is to provide an improved arrangement of superheaters or reheaters or like elastic fluid heating apparatus whereby burning thereof is prevented.

Another object of my invention is to provide an improved arrangement for regulating the load on a superheater or reheater and equally distributing a load among a plurality of reheaters.

Still another object of my invention is to provide temperature regulating means for a reheater between a high pressure and a low pressure elastic fluid engine whereby a constant temperature of the fluid supplied to the 25 low pressure engine is maintained.

For a consideration of what I believe to be novel and my invention, attention is directed to the following description and the claims appended thereto in connection with 40 the drawing which forms a part of my specification.

In the drawing I have shown by way of example a reheating arrangement of the type specified in combination with a compound 45 turbine embodying my invention.

Referring to the drawing, 1 and 2 designate the elastic fluid generators or boilers for supplying elastic fluid such as steam to an elastic fluid engine shown as two turbines or elastic fluid consumers, a high pressure turbine 3 and a low pressure turbine 4. 5 is the conduit for conveying the steam from the boilers to the inlet of the high pressure turbine 3, whence a portion thereof may be conveyed directly to the low pressure turbine 4 50 through a conduit 6 including a valve means 7. 8 is a condenser for the low pressure turbine.

For reheating at least a portion of the exhaust steam from high pressure turbine 3, I 60 provide two reheaters 9 and 10 respectively which in the present instance are shown as being combined with boilers 1 and 2 respectively to form single units therewith. With such an arrangement the fire gases leaving 65 the boiler pass through the reheater and convey heat to the fluid to be reheated. The inlets 11 and 12 of the reheaters are connected to inlet conduits 13 and 14 respectively. The latter are connected to a supply conduit 70 15, which in turn is connected to the exhaust of the high pressure turbine. The outlets 16 and 17 of the reheaters are connected by outlet conduits 18 and 19 respectively to a discharge conduit 20, which in turn is connected 75 to inlet 21 of the low pressure turbine. It will be noted that the two reheaters are connected in parallel between the high pressure and the low pressure turbines.

The arrangement so far described may be 80 considered as typical of any arrangement for reheating the exhaust elastic fluid of a high pressure engine and conveying the superheated elastic fluid to a low pressure engine.

Provided in conduits 15 and 20 are valve 85 means 22 and 23 respectively for manually regulating the amount of steam passed through the reheaters. This regulation may also be performed by properly adjusting valve means 7 in conduit 6. In order to 90

maintain substantially constant the temperature of the fluid passed through the superheaters or reheat^{ers} I provide means for automatically regulating the amount of steam or like elastic fluid passed through the reheat^{ers}. This has been shown in the present instance as comprising valve means 24 and 25 provided in conduits 13 and 14 respectively. These valve means are regulated or adjusted by means of temperature responsive devices 26 and 27 respectively in terms of temperature of the steam in conduits 18 and 19 respectively. Each temperature responsive device includes a casing 28 divided into a left-hand and right-hand half by a diaphragm 29 connected to the movable member of the valve means and biased towards closing position by a spring means 30 between the left-hand half and the diaphragm. Communicating with the right-hand half is a pipe 31 having a sealed end projecting into conduit 18.

Temperature responsive devices of this kind are known. Their operation is as follows: An increase in temperature of the fluid passed through outlet conduit 18 causes an increase in pressure of a gas contained in tube 31 and the space defined by the right-hand half of the casing and the diaphragm, to the effect that the expanding gas in the casing causes valve 24 to be moved towards opening position. Thus, if the temperature of the superheated steam increases, valves 24 and 25 are moved towards open position, to the effect that more steam is passed through the reheat^{ers} and less steam is passed through conduit 6, with the result that the temperature of the steam supplied to the low pressure turbine after being reheated remains substantially constant. Valve means 24 and 25 and the temperature responsive devices for adjusting these valve means in my arrangement also cause a uniform distribution of load among the reheat^{ers} connected in parallel, that is, if for example the available heat of the fire gases increases in one of the reheat^{ers}, for instance, of reheat^{er} 1, it causes an opening of valve 24, to the effect that relatively more steam is passed through reheat^{er} 1 and less steam through reheat^{er} 2.

According to my invention I provide safety valve means for discharging elastic fluid from the reheat^{ers} when the temperature thereof reaches a certain value and means for passing live elastic fluid through the reheat^{ers}. In the present instance I have shown a safety valve 32 in supply conduit 20 for discharging elastic fluid to the atmosphere or any suitable point such as a preheat^{er}, not shown. 33 is a temperature responsive device similar to the temperature responsive devices 26 and 27 and including conduit means 34 and 35 having sealed ends projecting into the reheat^{ers} 9 and 10 respectively. If the temperature in one of the reheat^{ers}

increases beyond a certain value, a gas contained in conduits 34 and 35 expands and causes opening of the safety valve. 36 is a conduit for directly conveying live elastic fluid from conduit 5, through conduit 15, to the reheat^{ers}. Provided in this conduit is a valve means 37 which is regulated by a pressure responsive device 39 including a conduit 40 connected to conduit 15. Pressure responsive device 39 is similar to the temperature responsive devices described above except that conduit 40 has an open end connected to conduit 15 so that the pressure of the elastic fluid passed through conduit 15 acts directly on the diaphragm provided in casing 41. A certain decrease in pressure in conduit 15 causes opening of valve 37, and vice versa.

The operation of the arrangement is as follows: A sudden decrease of load on the turbine causes a corresponding decrease of the amount of steam passed through the reheat^{ers}. This effects an increase in temperature of the reheated elastic fluid. As soon as the temperature reaches a certain predetermined value, the temperature responsive device 33 causes the safety valve or blow-off valve to open. This causes a sudden decrease in pressure in conduits 20 and 15, to the effect that the pressure responsive device 39 connected to conduit 15 effects opening of valve 37, thus permitting live elastic fluid being directly supplied from conduit 5, through conduit 15, to the reheat^{ers} 9 and 10. The circulation of live elastic fluid through the reheat^{ers} prevents burning of the latter. The live elastic fluid supplied to the reheat^{ers} through conduit 36 forms a cooling medium for the reheat^{ers}. Thus, from another aspect, conduit 36, valve 37 and the pressure responsive devices for regulating this valve form in substance a means for conducting a cooling medium to the reheat^{er} or reheat^{ers} in terms of pressure conditions existing in the supply or discharge conduit.

With my invention I have accomplished a simple and reliable arrangement for protecting reheat^{ers}, superheat^{ers} and like heating apparatus against the danger of burning of the pipes or conduits thereof during periods of low load of an apparatus to which the superheated elastic fluid is supplied, that is, when little elastic fluid is being conveyed through the superheat^{ers}.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent of the United States is:

1. In a reheating arrangement, an elastic fluid consumer, a reheat^{er}, a conduit for conducting fluid from the consumer to the reheat^{er},

- heater, another conduit for discharging fluid from the reheater, another elastic fluid consumer connected to the other conduit, safety valve means in the discharge conduit, means including a device responsive to temperature changes of the reheater for actuating the safety valve means, and means including a valve for supplying cooling fluid to the reheater in terms of pressure changes in one of the first named conduits. 5
2. In a reheating arrangement, an elastic fluid consumer, a plurality of fire gas-heated reheaters, a fluid supply conduit receiving fluid from the consumer, a fluid discharge conduit, another elastic fluid consumer connected to the discharge conduit, an inlet conduit for each reheater connected to the supply conduit, an outlet conduit for each reheater connected to the discharge conduit, a valve means in each inlet conduit, temperature responsive devices for controlling said valve means in response to the temperature changes in the corresponding outlet conduits, a safety valve in the discharge conduit, means for actuating the safety valves in response to temperature changes of one of the reheaters, and means for supplying cooling fluid to the supply conduit in response to fluid pressure changes in said supply conduit. 10 15 20 25
3. In a power plant, an elastic fluid generator, an elastic fluid engine receiving elastic fluid from the generator, a fire gas-heated reheater for superheating the exhaust elastic fluid of the engine, a consumer receiving elastic fluid from the reheater, and means for automatically supplying live elastic fluid to the reheater in terms of pressure conditions of the exhaust elastic fluid of the engine to prevent burning through of the reheater. 30 35 40
4. In a power plant, an elastic fluid generator, an elastic fluid engine receiving elastic fluid from the generator, a fire gas-heated reheater for superheating the exhaust elastic fluid of the engine, a consumer receiving superheated elastic fluid from the reheater, means for supplying live elastic fluid to the reheater in terms of pressure conditions of the exhaust elastic fluid of the engine, safety valve means for the reheater, and means for operating the safety valve means in terms of temperature conditions of the reheater. 45 50 55
5. In a power plant, elastic fluid generating means, a high pressure and a low pressure engine, a conduit for conveying elastic fluid from the generating means to the high pressure engine, another conduit including a valve means for conveying a portion of the exhaust elastic fluid of the high pressure engine to the low pressure engine, a fire gas-heated reheater, a supply conduit for conveying exhaust elastic fluid of the high pressure engine to the reheater, a discharge conduit for conveying the superheated elastic fluid from the reheater to the low pressure 60 65
- engine, a safety valve means in one of the last named conduits, means for operating the safety valve means in terms of temperature conditions in the reheater, a conduit including a valve means for supplying live elastic fluid to said supply conduit, and pressure responsive devices for actuating the last named valve means in terms of pressure conditions in the supply conduit. 70
- In witness whereof, I have hereunto set my hand. 75
